UNITED STATES PATENT OFFICE.

THOMAS O. MILLER, OF SAN ANTONIO, TEXAS.

STREET-TRAFFIC SIGNAL.

1,353,999.

Specification of Letters Patent. Patented Sept. 28, 1920.

Application filed November 26, 1917. Serial No. 204,040.

To all whom it may concern:

Be it known that I, THOMAS O. MILLER, a citizen of the United States of America, and a resident of San Antonio, in the county of Bexar and State of Texas, have invented certain new and useful Improvements in Street-Traffic Signals, of which the following is a specification.

The primary object of this invention is to provide an improved street traffic signal that is operable from the center of the intersection of streets, or can be operated from the curbing of the street intersection.

Another object is to provide a street traffic signal with an improved clutching arrangement which is related to the methods of operation relative to whether the operator desires to operate the signal device from the center of the street intersection or from the curbing.

Other and further objects will appear in the specification and be specifically pointed out in the appended claims, reference being had to the accompanying drawings exemplifying the invention, and in which,

Figure 1 is a side elevation of this improved street traffic signal, parts being broken away.

Fig. 2 is a plan view of this improved device on a reduced scale, showing its location and manner of suspension relative to intersecting streets.

Fig. 3 is a fragmentary vertical section taken on the line III—III of Fig. 1.

Fig. 4 is an enlarged fragmentary view showing that portion of the device containing the clutch which is essential to the operation of this improved signal.

Fig. 5 is an enlarged plan view taken on the line V—V of Fig. 4.

Fig. 6 is a side elevation of a modified form of suspended signal showing its relation to diagonally opposed corners.

Fig. 7 is a fragmentary plan view of Fig. 6.

Referring to the drawings, this improved traffic signal comprises a vertically arranged supporting rod 1 which is turnably mounted at its upper end to a strain plate 2, said strain plate being suspended by the guy wires 3 and 4, said guy wires being secured to said plate and to the posts 5 and 6 which are located on diagonally opposite curbings 7 and 8, respectively. Secured to the upper

end of the supporting rod 1 is a lever 9, the outer end of said lever having a swivel

joint 10 secured thereto. Secured to said swivel joint 10 is one end of the cable 11, said cable being mounted over a pulley 12, said pulley being carried by the clamping bracket 13 which is mounted adjacent the upper end of the post 5, said cable having its opposite end 14 extend to a point adjacent the curbing 7.

Mounted on the supporting rod 1 adjacent the under side of the strain plate 2 is a coil spring 15, said spring being secured at one end to a bolt 16 which is carried by the strain plate 2, the opposite end of said spring being secured at 17 to the rod 1.

Turnably mounted on said rod 1 is a sleeve 18, and carried by the lower end of said sleeve is a housing 19, said rod 1 extending into said housing, and having a shoulder 20 secured to the lower end thereof.

Mounted in said housing and abutting the shoulder 20 is a spring 21, said spring at its opposite end abutting the lower end of the sleeve 18. Formed on said sleeve 18 are a series of ears 22, said ears being for the support of pairs of indicator arms 23 and 24, said pair of indicator arms 23 bearing the direction sign to Go on each side, whereas the pair of arms 24 bear the direction sign to Stop on each side.

Depending from the lower end of the housing 19 are a pair of oppositely disposed ears 25, and horizontally arranged in said ears is a pin 26, and removably mounted on said pin is a hook 27 of a lamp 28. Secured to the under side of said lamp 28 is a loop 29, said loop being for the securing of the hook 30 of a turning pole 31.

Carried by the turning pole 31 is an umbrella 32, and secured to the lower end of said pole is a turning handle 33. Formed in the sleeve 18 adjacent the upper end thereof is a slot 34, the length of said slot being approximately one-quarter of the circumference of said sleeve.

Formed in the lower wall of said slot are a pair of grooves 35, and centrally arranged between said grooves is another groove 36. Secured to the rod 1 is a horizontally arranged pin 37 extending in said slot 34, said pin being normally engaged in one of the grooves 35 on account of the spring 21 bearing against the sleeve 18.

In the operation of this improved street traffic signal, the pairs of indicator arms 23 and 24 are adapted to be moyed to alining

positions relative to the intersecting streets so that the signal will indicate Go on one street and Stop on the other street.

If it is desired for the operator to operate the signal from the center of the street intersection, the operator will engage the hook 30 of the turning pole 31 on the loop 29, as it is to be noted that this improved device is suspended a distance above the traffic from the strain plate 2.

When the operator desires to shift the signal from a set position, a pull is exerted on the turning pole 31, which will cause the sleeve 18 to be moved downwardly against the pressure of the spring 21, thereby disengaging the groove 35 from the pin 37, and from the disclosure of Figs. 1 and 4 of the drawings, the operator will then move the turning pole to the left until the wall 38 of the slot 34 will engage the pin 37; then the operator on releasing the pole and the spring 21 will force the sleeve 18 upwardly until the other groove 35 of the slot 34 engages said pin 37. On account of the length of the slot 34, the sleeve 18 is only permitted to be moved one-quarter of a turn. Therefore the aforesaid operation of said sleeve 18 and indicator arms 23 and 24 carried thereby will shift the directions to the traffic, in which the traffic on one street will stop and the traffic on the other street will have the right of way to cross.

When the operator again desires to shift the directions as indicated by the indicator arms 23 and 24, after moving the sleeve 18 downwardly to release the sleeve from being held against turning by the pin 37, the turning pole 31 is turned to the right and in the opposite direction until the pin 37 is engaged by the wall 39 of the slot 34.

This improved device as afore related can also be operated from the the curbing, in which the turning pole 31 is disengaged from engagement with the loop 29, and the operator will take his place adjacent the post 5 on the curbing 7, and upon pulling the cable 11, the lever 9 will be moved until it abuts the upper end of the bolt 16, the movement of said lever causing the supporting rod 1 to be turned, and since the sleeve 18 is normally locked to said rod 1 by engagement of the pin 37 of the rod 1 in either one of the grooves 35; said sleeve and indicator arms 23 and 24 carried thereby will be turned one-quarter of a revolution.

While the traffic is following the directions indicated by the arms 23 and 24 the operator will bear on the cable, thereby holding the indicator arms in their moved positions, and when the operator releases the cable, the spring 15, which is secured to the rod 1 and strain plate 2, will turn said rod and sleeve 18 in the opposite direction to which they were just turned, and the movement of one-quarter revolution rearwardly

will be stopped when the lever 9 engages the bolt 40 which is secured to the strain plate 2.

When the operator has to leave his post of duty, and the traffic will have to take care of itself as regards regulations, the sleeve 18 is pulled downwardly and turned approximately half way around on the rod 1 until the centrally arranged groove 36 is in position to engage the pin 37, and when said pin 37 is engaged in said groove 36, the indicator arms 23 and 24 will be arranged in positions diagonally of the street corners, which will indicate to the traffic on both streets to be cautious.

If it is desired to dispense with the lamp 28 which is adapted to indicate in accordance with the arms 23 and 24, the hook 27 of said lamp is disengaged from the pin 26, said pin then being engaged by the hook 30 of the turning pole 31.

The showing made in the drawings relative to the cable 11 and pulley 12 being operably related to the lever 9, can if desired be replaced by a system of turning bars and levers, in which the turning bar will be located adjacent one of the curbing posts.

Referring more particularly to Figs. 6 and 7, the disclosure therein shown calls for more of a direct construction, in which the vertically arranged depending rod 41, is turnably supported at its upper end in the strain plate 42, said strain plate being held in its suspended position by the guy wires 43 and 44.

Secured to the upper end of the rod 41 above and bearing on said strain plate is a cross lever 45, comprising a pair of oppositely disposed arms 46. The guy wires 43 and 44 are strung from diagonally opposed posts 47 and 48, respectively, and supported by the guy wire 44 is a strain plate 49, said strain plate being adjacent the post 48 and above the curbing 50.

Turnably mounted in the strain plate 49 and depending therefrom is a signal actuating rod 51, and secured to the upper end of said rod above said plate 49 is a cross lever 52 having oppositely disposed arms 53. Secured to each of said arms is a shifting cable or rod 54, the opposite ends of said rods being connected to the respective arms 46 of the cross lever 45.

Carried by the end of the rod 51 is a pin 55, said pin being for the engagement of a turning pole 56. Carried by the lower end of the rod 41 is a pin 57, said pin to be engaged by the turning pole 56.

Secured to said rod 41 is a plurality of indicator arms 58. In Fig. 6 the turning pole 56 is in a position of operating the signal arms 58 from the curbing, in which when said turning pole 56 is turned, the signal rod 51 is operated, thereby exerting the pulling or pushing force of the cables or rods 54, and incidentally turning the cross

lever 45, thereby operating the signal supporting rod 41.

When it is desired to operate the signal from the center of the street intersection, the turning pole 56 is mounted on the pin 57, said turning pole when operated applying direct motion to the rod 41 and signal arms 58.

What I claim is:

10 1. A street traffic signal comprising a turnably mounted vertically suspended member, an indicator turnably mounted on said member, means for operating said member from therebeneath, and other means for 15 operating said member independently from said first mentioned means, located at a distance therefrom.

20 2. A street traffic signal to be operated from the street curbing or from the street center comprising a turnably mounted depending member, an overhead suspension for said member, a plurality of indicator arms horizontally arranged and turnably mounted on said member, detachable depending means for turning said indicator arms on said member from the street, and other means for operating said arms from 25 the street curbing.

30 3. A street traffic signal comprising a vertically arranged, turnably mounted member, an overhead suspension for said member, an indicator turnably mounted on said member, means for locking said indicator to said member, and means for operating said 35 member from therebeneath.

40 4. A street traffic signal comprising a vertically arranged suspended member, a sleeve turnably mounted on said member, indicators carried by said sleeve, a clutching mechanism coöperable with said member and said sleeve, and means for operating said member and said sleeve arranged beneath said member.

45 5. A street traffic signal comprising a suspended strain plate, a vertically arranged

turnably mounted member supported by said plate, a sleeve turnably mounted on said member, indicator arms carried by said sleeve, a clutch mechanism provided by said member and said sleeve, means for operating 50 said member and said sleeve, and means depending from said sleeve for operating said sleeve independently of said member.

6. An overhead street traffic signal comprising a strain plate, a vertically arranged 55 turnably mounted member supported by said plate, indicator arms carried by said member, a second strain plate, a vertically arranged turnably mounted member supported by said second mentioned plate, 60 means for connecting said turnably mounted members, and means for operating said indicator arms from either of said members.

7. A street traffic signal comprising a turnably mounted vertically suspended 65 member, a sleeve turnably mounted on said member, indicators carried by said sleeve, a clutching mechanism coöperable with said member and said sleeve, providing means for operating said member and said sleeve 70 together or independently of one another and depressing means for releasing said clutch and operating said member.

8. A street traffic signal comprising a turnably mounted suspended member, an indicator carried by said member, engaging means provided adjacent the lower end of said member and a detachable element vertically coöperable with said engaging means for turning said member.

9. A street traffic signal comprising a vertically arranged depending member, a sleeve slidably and turnably mounted on said member, indicators carried by said sleeve, a spring actuated clutch mechanism formed between said member and said sleeve, and detachable downwardly pulling means for releasing said mechanism and operating said sleeve independently of said member.

THOMAS O. MILLER.
